W. M. Chapman
Atty.

UNITED STATES PATENT OFFICE.

NORMAN E. GEE, OF ALTOONA, PENNSYLVANIA, ASSIGNOR OF ONE-HALF TO JOSEPH W. PARKS, OF ALTOONA, PENNSYLVANIA.

MILK RECEPTACLE.

Application filed August 11, 1922. Serial No. 581,182.

To all whom it may concern:

Be it known that NORMAN E. GEE, a citizen of the United States, residing at Altoona, in the county of Blair and State of Pennsylvania, has invented certain new and useful Improvements in Milk Receptacles, of which the following is a specification.

This invention relates to milk receptacles and has for its primary object an improved means whereby the receptacle cap can easily be removed without the use of the usual pointed metal cap remover or other instrument of a similar nature.

Another object of this invention is to provide means at the top of the bottle whereby the cap when pressed into the bottle will have its edge turned upward such that it is easily removed without the use of any instrument whatsoever.

A still further object of this invention is to provide a milk receptacle that will not have any obstruction on the internal periphery of the neck or at the top that will in any way interfere with the cleansing of the receptacle, or in any way obstruct the application of the usual paper cap which is generally used on such receptacles.

With these and many other objects in view which will be more readily apparent as the nature of the invention is better understood the same consists in the novel construction, combination and arrangement as will be seen more readily by reference to the drawings.

It will be quite readily understood by those skilled in the art to which this invention belongs that the same is susceptible of some structural change and modification without departing from the spirit or scope of the invention but a preferred and practical embodiment of the invention is shown in the accompanying drawings in which—

Figure 1 is a sectional elevation view of the milk receptacle having my invention applied thereto.

Figure 2 is a plan view of the receptacle shown in Figure 1 of the drawings.

Figure 3 is a view of the top of the receptacle showing the manner in which the receptacle cover is removed.

Similar reference numerals refer to similar parts throughout the several figures of the drawings.

In carrying out this invention no material

change is contemplated in the usual construction of the milk receptacle and no change whatever in the usual construction and form of the receptacle cover and to this end I provide a milk receptacle designated in its entirety by the numeral 10 having applied thereto a paper cap 11 which is usually pierced by a pointed instrument in order to disengage it from the top of the bottle after it has been attached thereto by a bottle filling and capping machine which is in general use at all milk bottling plants.

In order to obviate the necessity of using any pointed instrument whereby the receptacle cover is pierced in order to remove the cover, I construct the top of the receptacle as clearly shown in Figures 1 and 2 of the drawings.

On the interior of the neck adjacent the top 12 where the receptacle cover is adapted to fit, there is provided as an integral part of the receptacle a stopper seat S including a plurality of ledges designated by the numerals 13 and 14. The ledge 13 is preferably made crescent shape as illustrated in Figure 2 of the drawings the said crescent like formation terminating at 13^a. The ledge 14 is made in the form of a projection with an edge 15 over which the cover 11 is adapted to be bent when the same is removed as clearly illustrated in Figure 3 of the drawings.

The ledges 13 and 14, it will be noticed do not protrude sufficient into the opening at the top of the bottle to interfere in any way with cleansing the same, either by the revolving brush method or by the spray and nozzle method.

The cap 11 is placed in position on the top of the bottle by the usual bottle capping machine and is adapted to be removed by placing the fore finger on the cap immediately above the ledge 14, a downward pressure on the cap has the effect of causing the edge 17 of the cap to creep toward the center of the bottle while the edge 18 is turned upward as illustrated in Figure 3 of the drawings, such that it is easily removed by the thumb and fore finger, thus obviating in a very practical way the use of any instrument for removing the caps from milk bottles used as milk receptacles.

In order that some indication may be given whereby it is known where the cap

may be pressed downward by the forefinger a groove 19 is shown blown in the top surface of the neck of the bottle.

- From the foregoing it will be apparent 5 that the novel and distinctive feature of the invention is the provision of a novel seat S for the usual paper cap or stopper, the said seat consisting of a circular recess at the mouth of the bottle and an annular shoulder 10 forming the bottom of the recess, the edge 13^b of the shoulder forming the ledge 13 being eccentric to the axis of the circular recess, thereby providing fulcruming or bending points 13^a at substantially diametrically 15 opposite points of the bottle mouth. When finger pressure is applied to the flexible paper cap at a point between the fulcruming points 13^a the result will be that the cap will be bowed or somewhat folded diametrically, and due to the fact that the ledge 14 is positioned well within the seat the cap 20 will be forced upwardly over the ledge 15 to a sufficient degree to permit of finger engagement.
- 25 Without further description it is thought that the features and advantages of the present invention will be readily apparent to those skilled in the art, and it will of course be understood that changes in the form, proportion, and minor details of construction 30 may be resorted to without departing from the spirit of the invention or scope of the appended claims.

I claim:—

- 35 1. In combination, a milk bottle, a receptacle cover or cap adapted to be fitted to the top of the receptacle and a ledge upon which the receptacle cap is adapted to rest, said ledge being crescent shaped on one side, and

an oblong projection at the other side 40 whereby the edge of the cap adjacent the oblong ledge is turned upward by pressure placed on cap between the said ledge and the centre of the receptacle.

2. A receptacle of the class described including a cap seat, said seat consisting of a circular recess, the bottom of which is in the form of a ledge, a portion of which is concentric with the edge of the recess while another portion is eccentric to the axis of the 50 circular recess, and an offset projection formed from the edge opposite the eccentric edge thereof.

3. A receptacle having a mouth formed with a depressed circular recess having an 55 eccentric ledge, a cap seat, a flexible cap adapted to rest in said recess on the seat and means in the seat whereby downward finger pressure on the flexible cap will cause the same to bend one edge upward for finger engagement while the opposite edge moves toward the depression over the eccentric ledge.

4. A receptacle having a mouth formed with a depressed cap seat, a flexible paper cap adapted to rest in the seat, means in 65 the seat whereby downward pressure near the edge of the flexible cap will cause same to bend and flex the edge upward for finger engagement, means for permitting the opposite edge of the cap to move toward the depression without entering the receptacle and means on the receptacle mouth for indicating the point of application of downward finger pressure on the cap.

In testimony whereof he affixes his signature.

NORMAN E. GEE.
